UNITED STATES PATENT OFFICE

JOHN L. FRANZEN, OF OREGON CITY, OREGON

SUPPORTING DEVICE OR CATAFALQUE

Application filed June 27, 1931. Serial No. 547,281.

My invention relates to devices for supporting an object in a horizontal plane upon an uneven or inclined surface, and relates particularly to such devices commonly known as a catafalque adapted for supporting a casket or coffin over an open grave.

It is desirable, when funeral services are held in a cemetery, that the casket be supported over the open grave in a horizontal plane, irrespective of the slope of the ground, and that the means provided for such purpose be adapted to be concealed by draperies and flowers, or the like, and thus also conceal the open grave. It is further desirable that such means be adapted to permit the casket to be lowered into the grave without removing the said supporting means, whereby as many of the unpleasant and depressing parts of the service as possible will be hidden.

Therefore the object of my invention is to provide a simple but strong and economically manufactured supporting frame, conveniently adjustable to support an object specifically a coffin in a horizontal plane irrespective of the unevenness or slope of the surface upon which it is mounted.

A further and more particular object of my invention is to provide an adjustable perimetric frame adapted to be mounted upon the margin of an open grave and to support a coffin thereon and permit the latter to be lowered through the said frame into the grave by means of auxiliary devices supported upon the frame.

A still further object of my invention is to provide a supporting frame, foldable into a compact unit, whereby when not in use it may be conveniently stored and occupy but a minimum of space.

I attain my objects in a supporting frame comprising rectangular frame members, spaced diagonally arranged, supporting arms connecting said frame members, said arms pivotally secured at one end to one of said frame members and adjustably secured at the other end in the corresponding sides of said other frame member, means for securing said arms in adjusted position relatively to said frame members.

These and other incidental features of my

invention, the details of construction and mode of adjustment are hereinafter fully described with reference to the accompanying drawings.

In the drawings:

Fig. 1 shows a side elevation of my supporting device and illustrates a coffin supported thereon by means of auxiliary devices;

Fig. 2 shows a perspective view of the same;

Fig. 3 shows a fragmentary sectional view of my invention and illustrates my supporting device adjusted to rest upon an inclined surface and support the coffin in a horizontal plane;

Fig. 4 shows a section taken on the line 4—4 of Fig. 3;

Fig. 5 shows an enlarged fragmentary view of the means by which the cross arms are adjustable in the frame;

Fig. 6 shows a section taken on the line 6—6 of Fig. 5;

Fig. 7 shows in a view similar to Fig. 5 further details of the means by which the cross arms are adjustable on the frame;

Fig. 8 shows a fragmentary perspective view of one cross arm and the means by which it is adjustable in the frame, the various parts being separated to further illustrate the details of construction; and

Fig. 9 shows a plan view of my supporting device and illustrates how the coffin is supported thereon by auxiliary devices.

Referring now to the figures, my invention comprises similar rectangular frame members *a*, *b*, constructed preferably of light angle iron and provided with diagonally arranged arms *c* pivotally mounted on the sides of the frame member *a*, as at *d*, for movement in the plane of the respective sides and adjustably connected to the corresponding sides of the frame member *b* in slots *e*, hereinafter further described. Similar arms *c'*, *f'* are provided connecting the ends of the frame members *a*, *b*, which are pivoted to the frame member *a* as at *d'*, and are adjustably secured in slots *e'*, similar to the slot *e*.

Similar diagonally arranged arms *f* are pivotally mounted on the frame member *b*,

as at *g*, and slidably connected to the frame member *a* in slots *h* by means of bolts 2 and wing nuts 2*a*.

By these means a perimetric supporting frame is provided adapted to be mounted upon the margin of a grave, see Figs. 3 and 4, which may be adjusted in the slots *e* and *h* as required to position the frame member *a* in a horizontal plane irrespective of the inclination of the ground and to support a coffin thereon, as illustrated in Fig. 1.

In order to permit the coffin to be lowered through the said perimetric frame, I provide a standard lowering device, see Fig. 9, comprising parallel shafts 3, provided with pulleys which have wound over them broad belts 5, upon which the coffin is supported and which by rotating the shafts 3 in unison and in opposite directions will unwind the said belts and lower the coffin into the open grave.

Brace members *u* and *v* are provided, respectively, at the corners of the frame members *a*, *b*, for strength and to provide in the case of the frame member *a* a supporting surface for the said lowering device.

The arms *c* and *c'*, *f*' are adjustably secured in the slots *e* and *e'*, respectively, of the frame member by means of bolts *p* provided with wing nuts *p'* and engageable in notches *q* provided in the said slots.

A slide member *r* is provided between the arm and the frame side having an opening *s*, one end of which is inclined as at *s'*, through which the bolts *p* project. By moving the slide *r* so as to cause the bolt *p* to ride upward on the incline *s'*, the bolt *p* will be disengaged from the notches *q* and held so, to permit the ready adjustment of the arms to position the frame member horizontally, irrespective of the slope of the ground.

As illustrated in Figs. 3 and 4, my supporting frame is adjusted by releasing the bolts *p* and disengaging them from the notches *q* by the slides *r*, and then after manually positioning the frame member *a* so as to lie in a horizontal plane, I move the slide *r* so that the bolts *p* will slip into the notches *q* and then tighten the bolts *p* by means of the wing nuts *p'*.

In order to conveniently disassemble my supporting frame into two end sections and two side sections, so that it may be readily carried and transported, I have provided removable bolts 2, 3, for securing the brace members or plates *u* and *v* to the sides of the frame members *a*, *b*. Such construction permits my supporting frame to be readily separable by the removal of the said bolts and to be as readily assembled by securing them in place.

I claim:

1. A coffin stage comprising, upper and lower elongate rectangular companion frames, diagonal arms connecting the ends of said frames, said arms pivoted at one end to one frame and movably secured at the other end to the companion frame, said arms adapted to support the upper frame of the stage parallel or obliquely with the base, whereby to arrange the upper frame in a horizontal plane irrespective of the slope of the ground on which the stage is placed.

2. A coffin stage comprising upper and lower elongate rectangular companion frames, each composed of angle iron and cornered brace plates, diagonal arms connecting the ends of said frames, said arms pivoted at one end to one frame and movably secured at the other end to the companion frame, said arms adapted to support the upper frame of the stage parallel or obliquely with the base, whereby to arrange the upper frame in a horizontal plane irrespective of the slope of the ground on which the stage is placed.

2. A coffin stage comprising upper and lower elongate rectangular companion frames, each composed of angle iron and cornered brace plates, diagonal arms connecting the ends of said frames, said arms pivoted at one end to one frame and movably secured at the other end to the companion frame, said arms adapted to support the upper frame of the stage parallel or obliquely with the base, whereby to arrange the upper frame in a horizontal plane irrespective of the slope of the ground on which the stage is placed.

JOHN L. FRANZEN.
